UNITED STATES PATENT OFFICE

2,087,239

LIGHTING AND AIR CONDITIONING DEVICE

William A. Brown, Philadelphia, Pa.

Application February 17, 1936, Serial No. 64,240

19 Claims. (Cl. 240—2.16)

The object of this invention is to provide a commercially practical means of obtaining direct-indirect lighting and direct-indirect air circulation in a single inexpensive device for use in homes, offices, apartments, etc., with said lighting and air circulating means surrounded by a shade and so co-ordinated that flicker is eliminated to such an extent that it can be disregarded.

A further object of this invention is to provide means whereby high capacity light bulbs of 100 watts to 500 watts rating may be operated above a revolving variable speed propeller and in close proximity thereto, without causing flicker at low speed or glare at any time.

15 A further object of the invention is to provide adequate means for permitting a continuous positive flow of air past said light bulb to prevent an accumulation of excess heat, and, at the same time, to prevent any of the radiant heat generated by said bulb from reaching and damaging said propeller or the motor that drives it.

Another object of the invention is to provide a compact, shallow open ended ventilated reflector-diffuser enclosing the light bulb, comprising a 25 main diffuser portion with good light transmitting qualities and a co-operating secondary reflector portion with good reflecting qualities, and, in many cases, opaque in character to prevent heat penetration as well. To obtain the best results, the reflector member is preferably mounted in close proximity to said light bulb and has substantially the same contour of said light bulb.

Another object of this invention is to provide instantly removable suitable means to insure the 35 proper evaporation of definite quantities of water for humidification purposes by utilizing the radiant heat of the high capacity light bulb, enclosed within the reflector-diffuser and mounted above and in close proximity to the propeller and motor.

40 Another object of the invention is to provide an instantly removable open ended shade surrounding the light bulb, reflector, diffuser, propeller and motor, having an inner surface with high reflecting qualities capable of re-directing the 45 light rays of the bulb, originating in a plane above the propeller, to strike in a plane below the propeller to insure good lighting without flicker, and more particularly to prevent black spots when the propeller is at a standstill.

50 A further object of the invention is to provide a propeller having overlapping blades, so arranged that light rays can not pass through the central section of said propeller when revolving very slowly, or at a standstill.

55 A vitally important object of this invention is

to provide various parts comprising the general assembly, of such shape, materials and co-ordination that the possibility of noise is reduced to a minimum, without impairing the effectiveness of the air circulating, light producing and humidifying means employed. The slightest noise in a device of this character, is so intensified by the shade, particularly if it originates in the propeller, that extraordinary precautions must be taken to minimize it.

5 Since no one will accept or buy anything unconventional or queer in appearance, regardless of its efficiency, a very important feature of this invention is to provide a general assembly of such height and diameter as to permit the use of conventional size shades, to conceal it, and, to accomplish this, where a substantial volume of air is to be moved requiring the use of a larger propeller, it is preferable to employ a propeller having blades with a flat central portion and an outboard section of a steep pitch, thus permitting the reflector-diffuser to be mounted near the hub of the propeller, and effecting a substantial saving in height without reducing the volume of air moved or limiting the size of the light bulb, which 10 otherwise would be impossible to accomplish.

15 Other novel features of construction and advantage will hereinafter more clearly appear in the detailed description and the appended claims.

20 For the purpose of illustrating the invention, I have shown in the accompanying drawing typical embodiments of it, which in practice, will give satisfactory and reliable results. It is, however, to be understood that the various instrumentalities of which my invention consists can be variously arranged and organized, and my invention is not limited to the exact arrangement and organization of these instrumentalities as herein 25 set forth.

30 Figure 1 is a sectional elevation of a lighting and air conditioning device.

35 Figure 2 is a top plan view of a propeller employed and a portion of a guard.

40 Figure 3 is a top plan view of a portion of the device, showing more particularly the relation of 45 the humidifier to the shade frame, light and guard.

45 Figure 4 is a top plan view of a portion of the device showing more particularly the deflector and diffuser.

50 Figure 5 is a sectional view of a conventional socket for a two filament light bulb.

Similar numerals indicate corresponding parts.

55 Referring to the drawing: I designates a motor, which is pivotally mount-

ed on a support 2, and held in any desired position by means of the tightening devices 3 and the yoke 85. The special propeller 4 is enclosed within the wire guard 5 and mounted on the shaft 5 of the motor 1. The casting or stamping 6, to which the wire guard 5 is attached by any suitable means, has two opposed ears 7 to which the motor 1 is rigidly mounted by means of the studs and fastening devices 37, said casting being provided with a round central opening to receive the top of the motor 1. 8 designates an insulated knob mounted on the shaft of a special variable speed rheostat, concealed within the junction box section 29 of the casting 6, and is used to control the speed of the motor 1. 9 is the lever of a switch, also concealed within the junction box 29, which is used to control the porcelain socket 10 that is held in permanent position on the wire guard 5 by means of the tube 11, the nozzles 12, the drilled steel flat piece 13, the fastening devices 14, which hold the flat piece 13 permanently in position on the main supporting member 15 and which is welded to the wire guard 5.

25 The main supporting member 15 has the cone shaped open ended light transmitting diffuser 16, which is preferably of glass, rigidly attached to it by means of the metal members 17, which are held in permanent position on the support 15 by means of the fastening devices 18. The reflector 19, which may be of metal or a very dense glass but which is preferably of electrolytically brightened aluminum because of its permanent high reflecting qualities, is attached to the support 15 by means of the fastening devices 20. The stamped or cast metal member 35, which is designed to hold at least one pint of water to be evaporated by the radiant heat of the light bulb 21, has the narrow, inwardly projecting channel members 23 so arranged as to be in close proximity to the light bulb 21 to insure rapid evaporation of the water, and rests on the wire guard 5 by means of the ears 24, so that it can be instantly removed when not in use, such as in hot or warm weather when very rapid air movement is desired and humidification is unnecessary, as is the case in cold weather when artificial heat destroys the moisture in the air and a slight impedance in the free air circulated, which might be caused by the evaporating member 35, will not be noticed, especially since the motor is usually run at low speed in cold weather. The inwardly projecting channel members 23 are preferably made of electrolytically brightened aluminum in order to minimize the possibility of reducing the effectiveness of the light bulb 21. This is especially true where more than three such channel members 23 are employed.

25 designates the regular punched washer used to receive a finial or decorative piece, which has a three way support 36 that rests on the top ring of the wire guard 5 to allow instant removal of the shade 26, which encloses the entire assembly and which preferably has high reflecting qualities on its inner surface 27, if the entire assembly is to be inverted around its pivotal support. 28 designates the main lead wire that enters a hollow channel that runs around the top of the motor 1 to emerge in the junction box section 29 of the casting 6, where all the wires from the various parts are concealed and properly connected. The wire guard 5 is made in two sections and held together by the fastening devices 30, as, it is evident that the lower section, with 75 its spaced wire rings 31 must be first attached to

the casting 6 before the propeller 4 can be positioned on the shaft of the motor 1.

32 designates a round hole in the light transmitting diffuser 16 to permit easy insertion and removal of the light bulb 21 into or out of the 5 socket 10. In some instances, this opening 32 may be in the form of a slot.

Because of difficulty in preventing flicker in a device of this character, especially with the propeller 4 revolving at slow speed, it is desirable in 10 some cases to employ a special type of propeller having an opaque center 33, and blades 34, overlapping sufficiently to prevent any light from passing through the central portion of the propeller. In the event of the use of translucent 15 glass for the reflector 19, or in the event said reflector is opaque and reduced in diameter, there is a tendency for a greater light to be transmitted directly down on the user. Some of this light will pass through the outer portion of the propeller 20 where the blades do not overlap. Light rays passing through the member 16 in the directions indicated by arrows 39 in Figure 1, are redirected as shown when the shade 26 has an inner surface 27 of high reflecting qualities and compensate for 25 other light rays passing through the outboard portion of the propeller and thus practically eliminate flicker.

It will be seen from Figure 2 that the four blades 34 of the preferred type of propeller 4 30 used, overlap each other sufficiently at the center to prevent the passage of light from the light bulb 21, and, in combination with the solid central section 33, is thoroughly lightproof except at the outboard section where it is practically 35 flickerless at any speed, regardless of the intensity of the light bulb 21, when operated in combination with the reflector 19 and the diffuser 16 and the reflecting surface 27.

Figure 3 clearly shows the relation of the inwardly projecting members 23 of the fluid holding device 35 to the light bulb 21. It will be seen that the intense radiant heat, generated by the light bulb 21, is bound to cause evaporation of the liquid. The vapor so produced is circulated and re-circulated by the propeller 4, and adequate humidification is possible in artificially heated rooms where dryness may be a problem. 45

Figure 4 shows the comparative size and relation of the bottom opening of the diffuser 16 to 50 the reflector 19. The preferred method of rigidly holding the reflector 19 and the diffuser 16 to the main support 15 and in relation to each other will be clearly understood. As already stated, in many instances the circular opening 55 32 in the diffuser 16 may be replaced by a slot extending from the top of the diffuser to a position similar to the bottom of the circular opening 32 shown.

It is apparent that the tube 11, the nozzles 60 12, the drilled steel flat piece 13 and the socket 10 may be mounted on the main support 15, directly opposite to the position shown in Figure 1, in the event it is found desirable to use certain high capacity light bulbs which can not be 65 operated with the screw base above the filament, such as would happen if the superstructure was raised or inverted on the pivotal support 3 for spot lighting or infra-red treatments. This alternate position is clearly indicated in Figure 5, 70 where a special three way socket 86 for use with the modern two filament three light bulbs is shown, as well as the required triple lead wires 87, 88 and 89. It is to be understood, however, that it is within the scope of this invention 75

to use any type of bulb or socket desired in either position referred to.

It is obvious that a two filament high capacity light bulb, which is designed to provide three 5 distinct intensities of light, operating in conjunction with the herein described humidifier 35, will increase the different degrees of heat that may be applied to said humidifier 35 to control the amount of evaporation required.

10 Having thus described my invention what I claim as new and desire to secure by Letters Patent, is:

1. A device as herein set forth, comprising a light bulb, an open ended light transmitting member into which said bulb extends, a reflector for said bulb, said reflector being spaced from the light transmitting member to permit air circulation past said reflector and around the light bulb, a motor driven propeller mounted at 20 the inlet end of said light transmitting member, and a shade surrounding said bulb, light transmitting member and motor driven propeller and having its inner face provided with light reflecting qualities.

25 2. A device as herein set forth, comprising a light bulb, an open ended light transmitting member into which said bulb extends, a reflector for said bulb, said reflector being spaced from the light transmitting member to permit air circulation past said reflector and around the light bulb, a motor driven propeller mounted at the inlet end of said light transmitting member, a shade surrounding said bulb, light transmitting member and motor driven propeller and having 30 its inner face provided with light reflecting qualities, and a quick detachable humidifier mounted in close proximity to the light bulb.

3. A device as herein set forth, comprising a light bulb, an open ended light transmitting member into which said bulb extends, a reflector for said bulb, said reflector being spaced from the light transmitting member to permit air circulation past said reflector and around the light bulb, a motor driven propeller mounted at the 40 inlet end of said light transmitting member, said propeller having its blades overlapping and spaced from each other near their central portion to prevent flicker of the light, and a shade surrounding said bulb, light transmitting member and motor driven propeller and having its inner face provided with light reflecting qualities.

4. A device as herein set forth, comprising a light bulb, an open ended light transmitting member into which said bulb extends, a reflector for said bulb, said reflector being spaced from the light transmitting member to permit air circulation past said reflector and around the light bulb, a motor driven propeller mounted at the inlet end of said light transmitting member, said 45 propeller having its blades overlapping and spaced from each other near their central portion to prevent flicker of the light, a shade surrounding said bulb, light transmitting member and motor driven propeller and having its inner face provided with light reflecting qualities, and a quick detachable humidifier mounted in close proximity to the light bulb.

5. A device as herein set forth, comprising a light bulb, an open ended light transmitting member into which said bulb extends, a reflector for said bulb, said reflector being spaced from the light transmitting member to permit air circulation past said reflector and around the light bulb, a motor driven propeller mounted at the 50 inlet end of said light transmitting member and

having its blades projecting upwardly in such a manner as to form a space within which the light transmitting member is so disposed as to prevent any impedance of the air circulation and whereby a substantial reduction in overall height 5 is achieved, and a shade surrounding said bulb, light transmitting member and motor driven propeller and having its inner face provided with light reflecting qualities.

6. A device as herein set forth comprising a light bulb, an open ended light transmitting member into which said bulb extends, a reflector for said bulb, said reflector being spaced from the light transmitting member to permit air circulation past said reflector and around the light 15 bulb, a motor driven propeller mounted at the inlet end of said light transmitting member and having its blades projecting upwardly in such a manner as to form a space within which the light transmitting member is so disposed as to 20 prevent any impedance of the air circulation and whereby a substantial reduction in overall height is achieved, a shade surrounding said bulb, light transmitting member and motor driven propeller and having its inner face provided with light reflecting qualities, and a quick detachable humidifier mounted in close proximity to the light bulb.

25 7. A device as herein set forth, comprising a light bulb, an open ended light transmitting member into which said bulb extends, a reflector for said bulb and spaced from the light transmitting member to permit air circulation past said reflector and around the light bulb, a motor driven propeller mounted at the inlet end of said 30 light transmitting member, said propeller having its blades overlapping and spaced from each other near their central portion and its tipped portions projecting upwardly, and a shade surrounding said bulb, light transmitting member and motor driven propeller and having its inner 35 face provided with light reflecting qualities.

8. A device as herein set forth, comprising a light bulb, an open ended light transmitting member into which said bulb extends, a reflector for said bulb and spaced from the light transmitting member to permit air circulation past said reflector and around the light bulb, a motor driven propeller mounted at the inlet end of said light transmitting member, said propeller having its blades overlapping and spaced from 45 each other near their central portion and its tipped portions projecting upwardly, a shade surrounding said bulb, light transmitting member and motor driven propeller and having its inner face provided with light reflecting qualities, and a quick detachable humidifier mounted in close proximity to the light bulb.

50 9. A device as herein set forth, comprising a light bulb, an open ended member into which said bulb extends, a reflector for said bulb, said reflector being spaced from said member to permit air circulation past said reflector and around the light bulb, a motor driven propeller mounted at the inlet end of said open ended member, and a shade surrounding said bulb, open ended member and motor driven propeller.

55 10. A device as herein set forth, comprising a light bulb, an open ended member into which said bulb extends, a reflector for said bulb, said reflector being spaced from said member to permit air circulation past said reflector and around the light bulb, a motor driven propeller mounted at the inlet end of said open ended member, a shade surrounding said bulb, open ended member and motor driven propeller, and a quick 60

detachable humidifier mounted in close proximity with the light bulb.

11. A device as herein set forth, comprising a light bulb, an open ended member into which 5 said bulb extends, a reflector for said bulb, said reflector being spaced from said member to permit air circulation past said reflector and around the light bulb, a motor driven propeller mounted at the inlet end of said open ended member, 10 said propeller having its blades overlapping and spaced from each other near their central portion to prevent flicker of the light, and a shade surrounding said bulb, open ended member and motor driven propeller.

15. 12. A device as herein set forth, comprising a light bulb, an open ended member into which said bulb extends, a reflector for said bulb, said reflector being spaced from said member to permit air circulation past said reflector and around 20 the light bulb, a motor driven propeller mounted at the inlet end of said open ended member and having its blades projecting upwardly in such a manner as to form a space within which the open ended member is so disposed as to prevent 25 any impedance of the air circulation and whereby a substantial reduction in overall height is achieved, and a shade surrounding said bulb, open ended member and motor driven propeller.

13. A device as herein set forth, comprising 30 a light bulb, an open ended member into which said bulb extends, a reflector of said bulb and spaced from said member to permit air circulation past said reflector and around the light bulb, a motor driven propeller mounted at the 35 inlet end of said open ended member, said propeller having its blades overlapping and spaced from each other near their central portion and its tipped portions projecting upwardly, and a shade surrounding said bulb, open ended member 40 and motor driven propeller.

14. A device as herein set forth, comprising a motor driven propeller having its blades overlapping and spaced from each other, a source 45 of light in front of said propeller, a light transmitting reflector-diffuser between said propeller and source of light, and a shade surrounding said propeller, source of light and light transmitting reflector-diffuser.

15. A device as herein set forth, comprising a 50 motor driven propeller having its blades overlapping and spaced from each other, a source of light in front of said propeller, a light trans-

mitting reflector-diffuser between said propeller and source of light, a quick detachable humidifier mounted in close proximity to said source of light, and a shade surrounding said propeller, source of light, light transmitting reflector-diffuser and humidifier. 5

16. A device as herein set forth, comprising a motor driven propeller, a source of light in front of said propeller, a light transmitting reflector-diffuser between said propeller and source of 10 light, said propeller having its blades projecting upwardly in such a manner as to form a central space within which said reflector-diffuser may be disposed, and a shade surrounding said propeller, source of light and light transmitting 15 reflector-diffuser.

17. A device as herein set forth, comprising a motor driven propeller, a source of light in front of said propeller, a light transmitting reflector-diffuser between said propeller and source of 20 light, said propeller having its blades projecting upwardly in such a manner as to form a central space within which said reflector-diffuser may be disposed, a humidifier mounted in close proximity to said source of light, and a shade surrounding said propeller, source of light, light transmitting reflector-diffuser and humidifier. 25

18. A device as herein set forth, comprising a motor driven propeller, a source of light in front of said propeller, a light transmitting reflector-diffuser between said propeller and source of light, said propeller having its blades overlapping and spaced from each other, with their outboard 30 portions projecting upwardly in such a manner as to form a central space within which said reflector-diffuser may be disposed, and a shade surrounding said propeller, source of light, and light transmitting reflector-diffuser. 35

19. A device as herein set forth, comprising a motor driven propeller, a source of light in front 40 of said propeller, a light transmitting reflector-diffuser between said propeller and source of light, said propeller having its blades overlapping and spaced from each other, with their outboard portions projecting upwardly in such a 45 manner as to form a central space within which said reflector-diffuser may be disposed, a humidifier mounted in close proximity to said source of light, and a shade surrounding said propeller, source of light, light transmitting reflector-dif- 50 fuser and humidifier.

WILLIAM A. BROWN.
